U.S. Appl. No. 29/771,302, filed Feb. 22, 2021, Kumai, Nao.

* cited by examiner

Primary Examiner — Zenia I Bennett(74) *Attorney, Agent, or Firm* — Andrew F. Young; Nolte Lackenbach Siegel(57) **CLAIM**

The ornamental design for a cartridge for cosmetic applicator, as shown and described.

DESCRIPTION

FIG. 1 is a perspective view of a cartridge for cosmetic applicator showing my new design;

FIG. 2 is a front elevational view thereof;

FIG. 3 is a rear elevational view thereof;

FIG. 4 is an enlarged left side elevational view thereof;

FIG. 5 is an enlarged right side elevational view thereof;

FIG. 6 is a top plan view thereof; and,

FIG. 7 is a bottom plan view thereof.

The broken lines in the drawings depict portions of the cartridge for cosmetic applicator that form no part of the claimed design.
